Frederick Forsberg,
By Joshua A. Cook
his Attorney.

UNITED STATES PATENT OFFICE.

FREDERICK FORSBERG, OF CHICAGO, ILLINOIS.

FOOT-REST FOR BATH-TUBS.

1,019,775.

Specification of Letters Patent. Patented Mar. 12, 1912.

Application filed February 24, 1911. Serial No. 610,496.

To all whom it may concern:

Be it known that I, FREDERICK FORSBERG, a citizen of the United States, and a resident of the city of Chicago, county of Cook, and 5 State of Illinois, have invented certain new and useful Improvements in Foot-Rests for Bath-Tubs, of which the following is a specification.

My invention relates to improvements in 10 bath tub accessories and more specifically to a foot rest attachment for bath tubs.

The object of my invention is the production of a foot rest of the character mentioned which may be readily and quickly applied 15 for use and expeditiously detached when desired.

A further object is the production of a foot rest for bath tubs which will be of durable and economical construction, and efficient in use.

Other objects will appear hereinafter.

With these objects in view my invention consists in a foot rest for bath tubs characterized as above mentioned and in certain 25 details of construction and arrangement of parts, all as will be hereinafter more fully described and particularly pointed out in the appended claim.

My invention will be more readily understood by reference to the accompanying drawings forming a part of this specification, and in which—

Figure 1 is a side elevation of a conventional bath tub to which is applied a foot rest embodying my invention, Fig. 2 is a transverse section taken on line $x-x$ of Fig. 1, Fig. 3 is a perspective view of the foot rest detached, Fig. 4 is a perspective view of a slightly modified form of the foot rest, and 40 Fig. 5 is a section of a bath tub to which is applied a foot rest of the form shown in Fig. 4.

The preferred form of my invention as illustrated in the drawing comprises a body 45 formed of a single piece of metal which is in the form of an elongated band or strip. The upper end 1 of said body, as illustrated in Figs. 1, 2, and 3, is coiled upon itself in such a manner as to be adapted to snugly 50 engage the flared upper edge portion 2 of an ordinary metallic bath tub 3, the inner portion of said loop when in operative position engaging against the under side of said edge 2 of said bath tub, the outer convolution of said end resting against the upper

side of said body 2 as clearly shown in Fig. 2. The opposite end 4 of said body depends into the bath tub resting against the adjacent side of the latter, the extremity thereof terminating in an upwardly and outwardly 60 projecting portion 5 which is adapted to efficiently serve in the capacity of footrest. In order to better adapt said end 5 for engagement by the foot the same is preferably covered at its upper side with a rubber covering 65, such covering evidently serving to prevent slipping of the foot when resting upon said end.

The form illustrated in Figs. 4 and 5 is designed for employment in conjunction 70 with bath tubs whose upper edges are not flared as in the form shown in Figs. 1 and 2. To this end the under portion 1 of the device is bent back upon itself more abruptly than in the forms shown in Figs. 1, 2 and 3 75 so that, when the same is engaging the upper edge of the bath tub of the type shown in Fig. 5 the same will conform more nearly to the conformation of said edge and thus more effectually coöperate therewith.

A foot rest of the construction as set forth is adapted to be readily and quickly arranged in operative position upon a bath tub or to be expeditiously detached therefrom when desired, the same being adapted 85 when in operative position, to effectually serve the purpose for which it is designed. The device is of extremely simple construction, hence may be manufactured at a low cost, and the same is not susceptible to 90 readily becoming inoperative.

While I have illustrated and described the preferred construction for carrying my invention into effect, this is capable of variation and modification without departing 95 from the spirit of the invention. I therefore do not wish to be limited to the precise details of construction as set forth, but desire to avail myself of such variations as come within the scope of the appended claim.

Having described my invention what I claim as new and desire to secure by Letters Patent is:—

A device of the character described comprising a body formed of a single piece of flat metal, one end of said body being formed to embrace the upper edge of a conventional bath tub, the lower end of said body depending into the interior and against the inner side thereof, said lower end of said 110

body being turned upwardly and then outwardly terminating in an inwardly extending substantially horizontally disposed supporting portion, said supporting portion being slightly concave in form and a rubber covering for the upper edge of said supporting portion, substantially as described.

In testimony whereof I have signed my name to this specification in the presence of two subscribing witnesses.

FREDERICK FORSBERG.
